UNITED STATES PATENT OFFICE.

LAURA LOUISA JOHNSON, OF POCOPSON, PENNSYLVANIA.

RUG.

1,331,927.

Specification of Letters Patent. Patented Feb. 24, 1920.

Application filed April 19, 1919. Serial No. 291,265.

To all whom it may concern:

Be it known that I, LAURA LOUISA JOHNSON, a citizen of the United States, residing at Pocopson, in the county of Chester, State 5 of Pennsylvania, have invented a new and useful Rug; and I do hereby declare the following to be a full, clear, and exact description of the invention, such as will enable others skilled in the art to which it 10 appertains to make and use the same.

The present invention relates to a rag rug and a frame for making the same, and has for its object to provide an attractive and inexpensive rag composed rug or floor covering which can be made without the laborious work of sewing or stitching the rags together.

Further objects of the invention are to provide a rag rug which can be readily manufactured from ordinary rags and scraps of fabric, which is the same on both sides and can be reversed, and which can be easily made in different lengths and widths as may be desired.

With these and other objects in view the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:

Figure 1 is a top plan view of a partially completed rag rug and a frame which may be utilized in making the same.

Fig. 2 is a sectional view through the rug, taken on the line 2-2 of Fig. 1.

Fig. 3 is a sectional view taken on the line 3-3 of Fig. 1, being taken on a plane at right angles to Fig. 2.

Corresponding and like parts are referred to in the following description and indicated in all the views of the drawings by the same reference characters.

In carrying out the invention the rags are torn or cut into long strips, although these strips are not sewn together or secured by stitching. The laborious task of sewing the rags together, together with the expense of providing the large amount of thread necessary for that purpose, is thus entirely avoided. The rags are first taken and several strands *a* thereof twisted together to form a comparatively large cord 1.

The ends of successive strands are not stitched together, but are permitted to overlap and are twisted in with the other strands so that a continuous twisted cord 60 is provided. It will be understood that the successive lengths of rag elements *a* can be selected and arranged so that the strands will be pieced together at different points in the length of the twisted cord, thereby providing a comparatively thick rag composed cord which has sufficient tensile strength to hold the parts together, and which at the same time provides an excellent body or foundation from which to construct a rug. 70 This twisted rag cord is formed in a continuous length which is successively returned, as indicated at 2, so that the twisted cord lengths are arranged side by side and extend back and forth across the rug. 75 Binder or warp strips 3 of untwisted rag elements are woven back and forth through the twisted rag cord lengths 1, the twisted lengths 1 remaining substantially flat and straight while the untwisted rag strips 3 80 are woven back and forth around the same to hold them together. The body of the rug is thus composed of the twisting rag cords 1 and the untwisted rag strips 3 merely serve to hold the twisted cord members 1 together. 85 The strips 3 may be formed of successive lengths of rag which have the ends thereof tied or knotted together at 3^a, this being quicker and preferable to sewing.

A suitable frame for forming the rug is 90 shown by Fig. 1. This frame is substantially rectangular in shape and includes side pieces formed in overlapping sections 10^a and 10^b respectively. The overlapping portions of the sections of the side pieces are 95 held in an adjusted position by bolts 11, and the length of the frame can thus be increased or decreased, as desired. Adjustment is thus made for making a narrow rug or a wide rug, since the width of the rug is 100 determined by the length of the frame. Each end of the frame is formed with spaced cross bars 12 and 14, the outer cross bars 12 providing convenient handles for manipulating the frame, while the inner cross bars 14 are each provided with a series of notches adapted to receive the shanks of twisting hooks 15. These hooks are formed with collars 16 engaging the cross bars 14, and also with handles 17 by means of which 110 they can be manipulated. It will also be obvious that the hooks can be readily insert-

ed in position within the lateral notches of the cross bars, or removed therefrom, as may be desired. As the successive lengths of the twisted rag cord elements 1 are completed, the ends thereof are tied or otherwise temporarily secured to one of the hooks 15 and the handle 17 manipulated to complete the twisting of the cord, thereby, enabling the cord to be uniformly twisted from end to end, and also enabling all of the cord elements in the rug to be given substantially the same degree of twisting. A rug of uniform texture and thickness can thus be formed without difficulty. After the length of twisted rag cord has been given the finishing touches, the end thereof is looped around the particular twisting hook and the length of the cord element increased by twisting successive rag elements into the same until another cord element has been completed, when the operation is repeated at the opposite end of the frame. As the successive cord elements are completed, the untwisted binder or wrap strips 3 of rag elements are woven back and forth through the completed cord elements, the lengths of the binder strips 3 being increased by tying or securing additional rag elements thereto, as may be necessary. The frame may have a comparatively narrow width, since the twisting hooks can be shifted in the notches of the cross bars 14 and the frame advanced as the weaving of the rug proceeds. The width of the rug is thus determined by the adjustment of the two frame members, while

the length of the rug depends upon a number of twisted rag elements 1 which are formed and woven into the rug. The completed rug is reversible, different colors may be worked into the same to provide an attractive design or color scheme, and all stitching or sewing of the rags is avoided.

Having thus described the invention, what I claim as new and desire to secure by Letters Patent, is:

1. A frame for weaving rag rugs including end bars each of which has a series of notches therein, and twisting hooks fitted removably in the notches, said twisting hooks being interchangeable and formed with handles for rotating the same so that they can be used to twist successive lengths of twisted rag cords.

2. A frame for weaving rag rugs including side pieces formed in overlapping and adjustably connected sections, said frame being also formed with opposed end bars formed with corresponding lateral notches and a series of similar and interchangeable twisting hooks fitted removably in the notches and formed with handles, said hooks being adapted to be utilized for twisting the strands of rag cord elements.

In testimony whereof I have signed my name to this specification in the presence of two subscribing witnesses.

LAURA LOUISA JOHNSON.
